UNITED STATES PATENT OFFICE.

BASIL M. TAIT, OF DENVER, COLORADO.

DESIGN FOR A CANDY-BOX.

58,954.

Specification for Design.

Patented Sept. 6, 1921.

Application filed January 11, 1921. Serial No. 436,575. Term of patent 14 years.

To all whom it may concern:

Be it known that I, BASIL M. TAIT, a citizen of the United States, residing at Denver, in the county of Denver and State of Colorado, have invented a new, original, and ornamental Design for Candy-Boxes, of which the following is a specification, reference being had to the accompanying drawing, forming part thereof.

In the drawing:

Fig. 2 is an end view thereof.

I claim:

The ornamental design for a candy box as shown.

BASIL M. TAIT.
